UNITED STATES PATENT OFFICE.

RAY H. McIALWAIN, OF JACKSON, MINNESOTA.

END-GATE CONSTRUCTION.

Application filed October 16, 1924. Serial No. 744,019.

To all whom it may concern:

Be it known that I, RAY H. McIALWAIN, a citizen of the United States, residing at Jackson, in the county of Jackson and State 5 of Minnesota, have invented certain new and useful Improvements in an End-Gate Construction, of which the following is a specification.

This invention relates to improvements in 10 end gates for wagon bodies and has for its principal object to provide an end gate which is principally adapted to be used on wagon bodies in which grain or like is transported, the end gate having an opening 15 therein to permit the discharge of the grain from the wagon body, a closure being normally disposed over the opening to prevent the grain from accidentally leaking through the opening during the transportation of 20 the grain.

One of the important objects of the present invention is to provide a means for actuating the closure for the opening to permit the raising and lowering of the same 25 in a positive and efficient manner.

A further object is to provide an end gate of the above mentioned character, which is simple in construction, inexpensive, 30 strong and durable and furthermore adapted for the purposes for which it is designated.

Other objects and advantages of this invention will become apparent during the course of the following description.

In the accompanying drawing forming a 35 part of this specification and in which like numerals designate like parts throughout the same:

Figure 1 is a side elevation of the end gate embodying my invention, and

Figure 2 is a sectional view taken approximately on line 2-2 of Figure 1.

In the drawing wherein for the purpose of illustration is shown the preferred embodiment of my invention, the numeral 1 45 designates the end gate which is supported in the usual manner between the sides of the wagon body 2 at the rear end thereof. The end gate is provided with a substantially rectangular opening in the lower portion thereof as indicated at 3 whereby the grain in the wagon body may be discharged therefrom in the manner well known in the art.

A closure 4 is provided for the opening 50 3 and the same is slidable between the ver-

tically extending guide strips 5 and 6 secured to the end gate 1 adjacent the respective sides of the closure. Extending inwardly from the guide strips 5 and 6 and secured to the outer faces thereof are the 60 metallic strips 7 and 8 respectively, the same extending over the adjacent sides of the closure 4 for retaining the same in position between the guides 5 and 6 in the manner more clearly illustrated in Figure 65 2. Reinforcing metallic strips 9 and 10 are secured to the inner side of the end gate 1 and extends vertically adjacent the side of the opening 3.

The means for raising and lowering the 70 closure 4 with respect to the opening 3 in the lower portion of the end gate 1 comprises a pair of levers 11 and 12 respectively which are pivotally secured at their upper ends as at 13 to the upper portion 75 of the end gate 1 on the guide strips 5 and 6 respectively as clearly illustrated in Figure 1. A pair of links 14 and 15 respectively are secured at their lower ends as at 16 to the strips 17 and 18 respectively which are secured to the outer side of the closure 4 adjacent the respective sides thereof. The upper ends of the links 14 and 15 are pivotally secured to the intermediate portions of the levers 11 and 12 respectively 80 as illustrated at 19 and 20. The lower ends of the levers 11 and 12 provide handles for the purposes to be hereinafter more fully described.

Formed on the lower portion of each of 90 the links is the lateral extension 21, the outer end of which terminates in the hook 22 for engagement with the lower portion of each of the levers.

When the closure 4 is positioned over the 95 opening 3 so that the grain in the wagon body is prevented from being discharged through the opening, the levers and links are in the position shown in the full lines in Figure 1. When it is desired to raise 100 the closure 4 to uncover the opening 3 whereby the grain in the wagon body box may be discharged therethrough, the lower ends of the levers are raised upwardly in the direction of the arrows causing the 105 lower portions of the levers to become disengaged from the respective hooks 22 on the links 14 and 15 and when the levers and links assume the position shown in the dotted lines in Figure 1 of the drawing, 110

the closure 4 will be out of engagement with the opening 3 and will be disposed in the upper portion of the end gate whereby the grain may be discharged through 5 the opening 3. During the upward swinging movement of the levers, the side edges of the closure will slide along the adjacent side edges of the guides 5 and 6 on the outer side of the end gate.

10 The closure 4 is returned to its normal position over the opening 3 by swinging the free ends of the levers downwardly and when the lower portions of the levers engage the hooks 22, the downward swinging 15 movement of the levers is limited.

It will thus be seen from the foregoing description, that an end gate has been provided wherein the closure for the usual opening provided in the end gate may be 20 easily and efficiently operated, the parts being so arranged as to render the same positive in their operation.

While I have shown the preferred embodiment of my invention, it is to be understood that various changes in the size, shape and arrangement of parts may be resorted to without departing from the spirit of 25

the invention and the scope of the appended claim.

Having thus described the invention, what I claim is:—

The combination with the end gate of a wagon body and having an opening in the lower portion thereof, a closure for the opening slideable on the end gate, means for raising and lowering the closure comprising a pair of levers pivoted at their upper ends to the end gate on the respective sides of the closure, a pair of links pivoted at their lower ends to the closure adjacent the respective sides of the closure, said links being pivotally connected to the intermediate portions of the respective levers, the free ends of the levers providing actuating handles, and means for limiting the downward swinging movement of the levers, said means comprising lateral extensions formed on the lower portions of the links, the free ends of the extensions terminating in hooks for engagement with the lower portions of the respective levers.

In testimony whereof I affix my signature.

RAY H. McALWAIN.
